(12) United States Design Patent **(10) Patent No.:** **US D442,563 S**
Fayfield **(45) Date of Patent:** **** May 22, 2001**

(54) HOUSING FOR PHOTOELECTRIC CONTROL

(75) Inventor: **Robert W. Fayfield**, Excelsior, MN (US)

(73) Assignee: **Banner Engineering Corp.**, Minneapolis, MN (US)

(**) Term: **14 Years**

(21) Appl. No.: **29/120,863**

(22) Filed: **Mar. 28, 2000**

(51) LOC (7) Cl. **13-03**

(52) U.S. Cl. **D13/165**

(58) Field of Search **D13/165; D10/106; 250/221.1, 222.1, 206, 239**

(57) CLAIM

The ornamental design for housing for photoelectric control, as shown and described.

DESCRIPTION

FIG. 1 is a front perspective view of a housing for photoelectric control embodying my new design;

FIG. 2 is a rear perspective view of the housing for photoelectric control depicted in FIG. 1;

FIG. 3 is a front elevational view of the housing for photoelectric control depicted in FIG. 1;

FIG. 4 is a rear elevational view of the housing for photoelectric control depicted in FIG. 1;

FIG. 5 is a side elevational view of the housing for photoelectric control depicted in FIG. 1;

FIG. 6 is the other side elevational view of the housing for photoelectric control depicted in FIG. 1;

FIG. 7 is a top plan view of the housing for photoelectric control depicted in FIG. 1; and,

FIG. 8 is a bottom plan view of the housing for photoelectric control depicted in FIG. 1.
